MEANS FOR HEAT TREATMENT OF METAL

Clarence H. Watrous, Clinton, Conn., assignor
of one-half to Frederick A. Schwer, Clinton,
Conn.

Application July 6, 1936, Serial No. 88,940

7 Claims.

(Cl. 263—49)

This invention relates to new and improved means for heat treatment of metals.

It is the object thereof, among other things, to assemble metal articles to be heat treated in spaced relation to each other and subject the same to a substantially uniform heat.

In the drawing, which illustrates one of the several forms of mechanism that may be used in this invention, like numerals of reference indicate like parts in the several figures:

Figure 1 is a fragmentary view of the improved mechanism used in this invention;

Figure 2 is a fragmentary sectional view thereof; and

Figure 3 is an enlarged fragmentary view of a portion of the outside container with a support block associated therewith.

Heretofore articles to be heat treated have usually been assembled in a box with a carbonizer and then placed in a furnace. As the heat generally enters the furnace through the bottom or side walls thereof, its intensity adjacent to the inlets is greater than at other points. Therefore, that portion of the box adjacent to the heat inlet points is subject to a more intense heat than are the remaining portions. Likewise the articles are subject to the same unequal heat.

Attempts have been made to overcome the effect of this unequal application of heat by manually shifting the position of the box within the furnace and successively presenting new faces to the heat inlet points. As space must be provided to permit shifting the boxes, the number of boxes that can be placed within the furnace is thereby limited. Such shifting also prevents placing one box upon the top of other boxes. Thus the capacity of the furnace is considerably decreased. Opening the furnace door to shift the boxes creates a draft and permits the entrance of cold air that reduces the temperature of the furnace.

The above and other objections to the present method of heat treating metal are eliminated in the invention herein disclosed.

Referring now to the drawing, which illustrates one form of the means adapted to hold the articles, 10 indicates a container, shown herein as substantially rectangular in form and closed by a cover 11 with the joint between the cover and walls of the container filled with a cement 12, fire-clay, or the like, so as to form an air-tight joint.

Within this container is a similar container 13 which rests upon the blocks 14 in the container 10 and its open side is closed by a cover 15. Each of the blocks 14 has a platform 16 with projecting walls 17 upon two sides thereof.

The space between the platform and the bottom of the container 10 is substantially the same as that between the walls 17 and the inside of the walls of the container 10. When assembled,

the container 13 rests on the platforms 16 and thus positioned with an air space or chamber 18 surrounding it.

The joint between the cover 15 and the walls of the container 13 may or may not be sealed by cement, fire-clay or the like, as may seem most advisable.

The articles to be treated are designated 19 and are usually arranged within the container 13 in substantially the following manner. First, a layer of carbonizing material, which may be charcoal, ground bone, or the like, is placed on the floor of the container 13, then the articles 19, spaced apart from each other, are placed thereon, and then another layer of carbonizing material of substantially the same depth is placed in the container covering the articles positioned as above. Another group of articles is then placed thereon and this process is continued until the container 13 is filled. The cover 15 is then positioned and the container 13 placed within the container 10 supported by the blocks 14, after which the cover 11 is positioned and sealed and the entire unit placed in the furnace.

As the external heat is transmitted to the container 13 through the air chamber 18, it is uniform around all sides thereof, irrespective of the varying intensity thereof upon the exterior of the container 10. The articles are thus subjected to uniform heat irrespective of the relative position of the unit within the furnace. Thus the position of the containers within the furnace is not material and they may be placed either in contact with each other or with a limited open space therebetween sufficient to permit a circulation of hot air or on top of each other in tiers to the limit of the capacity of the furnace.

After the furnace has been loaded, the door thereof is not opened until the containers are finally removed. After the unit has been subjected to the proper degree of heat for a sufficient length of time, it is withdrawn, the covers of the containers 10 and 13 taken off and the articles removed. Thus an increased number of units may be placed within the furnace, the labor of changing the same is entirely done away with, and the heat within the furnace may be maintained at a more constant temperature because no blasts of cold air are admitted through the door opening.

If charcoal is used as a carbonizer it is preferable that the gas be removed therefrom before being placed in the container.

Rectangular containers only are shown and described, but containers of other shapes may be used, such as cylindrical, equally as well.

It is desirable that the articles should be subjected to a uniform heat in order to obtain the best results from the treatment. Under the old above described method the uneven application

of heat resulted in an imperfect heat treatment, while with the application of uniform heat, as disclosed in this invention, the article is uniformly heat treated throughout, and a better article 5 produced.

In practice it has been demonstrated that fine tools, for example razors, cannot be heat treated successfully by the old method but can with the means and method herein disclosed.

10 Within the scope of the appended claims minor changes and modifications, other than those above suggested, may be made.

What is claimed is:

15 1. In a unit of the type set forth wherein the parts are assembled and the device loaded before being placed in a furnace and the parts disassembled and unloaded after being removed therefrom, a portable outer container, an inner container for receiving the articles to be treated disposed within the outer container, and means to support the inner container so that its bottom, sides, ends and top walls are each spaced from the corresponding walls of the outer container whereby to provide heat passages, the bottom of 20 the outer container being formed to seat on and to be freely moved to selected positions on the floor of a furnace, the top of the outer container being formed to receive thereon the bottom of another outer container whereby to enable stacking of the outer containers within the furnace throughout the heating period.

25 2. In a unit of the type set forth, a portable outer container, an inner container for receiving the articles to be treated disposed within the outer container, means to support the inner container so that its walls are each spaced from the corresponding walls of the outer container whereby to provide heat passages, the bottom of the outer container being formed to seat on and to be 30 freely moved to selected positions on the floor of a furnace, a removable top for the outer container fixed and sealed in position before the unit is placed in the furnace and formed to receive thereon the bottom of another outer container whereby to enable stacking of the units 35 within the furnace throughout the heating period, and a removable top for the inner container spaced from the top of the outer container, the arrangement of all of said parts being such 40 that said heat passages are not disturbed or broken down until after the unit has been removed from the furnace and the parts thereafter 45 disassembled.

50 3. In a device of the type set forth; a portable outer container, an inner container for receiving the articles to be treated disposed within the outer container, and means to support the inner container so that its walls are each spaced from the corresponding walls of the outer container, whereby to provide heat passages, the outer container being formed to seat on and to be freely moved about selected positions on the floor of a furnace, and to receive thereon another outer container, whereby to enable stacking of the outer containers within the furnace throughout the heating period.

55 4. In a unit of the type set forth; a portable outer container having a separable cover; an inner container for receiving the articles to be treated, disposed within the outer container, hav-

ing a separable cover; and means to support the inner container so that its outside walls are each spaced from the corresponding inside walls of the outer container and thus providing a chamber therebetween, the outer container being formed so as to seat on and be freely moved to any position on the floor of the furnace, irrespective of the relative position of the heat inlet points of the furnace and to receive thereon another similar unit whereby to enable stacking of the units within the furnace throughout the heating period, the arrangement of all of said parts being such that the covers are positioned before the unit is inserted within the furnace and removed after being taken therefrom.

60 5. In a unit of the type set forth; a portable outer container having a separable cover with a sealed joint between it and the container; an inner container for receiving the articles to be treated, disposed within the outer container, having a separable cover; and means to support the inner container so that its outside walls are each spaced from the corresponding inside walls of the outer container and thus providing a chamber therebetween, the outer container being formed so as to seat on and be freely moved to any position on the floor of the furnace, irrespective of the relative position of the heat inlet points of the furnace and to receive thereon another similar unit whereby to enable stacking of the units within the furnace throughout the heating period, the arrangement of all of said parts being such that the covers are positioned before the unit is inserted within the furnace and removed after being taken therefrom.

65 6. In a unit of the type set forth; a portable outer container having a separable cover with a sealed joint of cement, fire-clay or the like, between it and the container; an inner container for receiving the articles to be treated, disposed within the outer container, having a separable cover; and means to support the inner container so that its outside walls are each spaced from the corresponding inside walls of the outer container and thus providing a chamber therebetween, the outer container being formed so as to seat on and be freely moved to any position on the floor of the furnace, irrespective of the relative position of the heat inlet points of the furnace and to receive thereon another similar unit whereby to enable stacking of the units within the furnace throughout the heating period, the arrangement of all of said parts being such that the covers are positioned before the unit is inserted within the furnace and removed after being taken therefrom.

70 7. In combination with a furnace; a heat treating unit composed of a plurality of containers, one within the other, and spaced therefrom with an air passage or chamber therebetween completely surrounding the inner of said containers; a cover for each of said containers, the cover for the outer container forming one wall of said air passage or chamber, the inner of said containers receiving the articles to be treated, the arrangement of all the parts of said unit being such that they are assembled before being placed in the furnace, in any convenient position in relation to each other and to the heat inlet points.

CLARENCE H. WATROUS.
